Term of patent 14 years

Int. Cl. D12—16

U.S. Cl. D90—16

FIG. 1

FIG. 2

FIG. 3

FIG. 1 is a top plan view of a bicycle seat, showing my new design;

FIG. 2 is a side elevational view thereof;

FIG. 3 is a front elevational view thereof;

FIG. 4 is a rear elevational view thereof;

FIG. 5 is a top plan view of a modified form thereof; and

FIG. 6 is a side elevational view of the embodiment of FIG. 5.

The characteristic features of my bicycle seat design reside in a low back rest which slopes downwardly and rearwardly from the top portion thereof and upwardly and rearwardly from the bottom portion thereof terminating in a rearwardly facing safety reflector, and in the opposite sides of the back rest which taper slightly toward the safety reflector.

I claim:

The ornamental design for a bicycle seat, substantially as shown and described.
